UNITED STATES PATENT OFFICE.

IRA H. TUBBS, OF CHICAGO, ILLINOIS.

HAME-TUG.

SPECIFICATION forming part of Letters Patent No. 297,474, dated April 22, 1884.

Application filed December 26, 1883. (No model.)

To all whom it may concern:

Be it known that I, IRA H. TUBBS, of Chicago, county of Cook, and State of Illinois, have invented certain new and useful Improvements in a Hame-Tug, of which the following is a full, clear, and exact description, that will enable others to make and use the same, reference being had to the accompanying drawings, forming a part of this specification.

10 This invention relates to improvements in hame-tugs, the object being to simplify the manner of constructing and connecting the several parts.

Figure 1 is a longitudinal vertical section of 15 the device embodying my improved features; Fig. 2, an edge view of the clip and plate connecting the same with the chape or buckle-piece; Fig. 3, a view in perspective of the inner side of the connecting-plate, and Fig. 4 a 20 top view.

Referring to the drawings, A represents the short leather tug, to which the several parts are attached, forming the connection between the hame and trace. This tug-strap consists 25 of the two parts a a' , which are stitched together along the edges, and form a sheath for the reception of the lower and longer arm, b , of the clip-iron B and the short leather part a^2 , which is also stitched along the edges and to 30 the parts a a' , thus forming a sheath between this top part, a^2 , and the upper side of the part a' for the insertion of the short arm b' of the clip B. The inner end of the part a^2 is loose, so that it can be raised up for the insertion 35 of the under side of the loop C, the stitches ending on a line with the end of the loop, which is also inserted underneath the inner end of the short arm b' , as shown in Fig. 1 of the drawings.

40 The metallic plate D forms the connection between the short arm b' of the clip and the chape or buckle-strap E, the plate being placed inside of the loop C, as shown in Fig. 1 of the drawings. The inner end of the plate D is 45 provided with the post a^3 , which passes down through corresponding perforations in the inner ends of the leather part a^2 and the short arm b' of the metallic clip B, and finally terminates in the under side of the loop C, thus 50 securing these parts with relation to each other. This end of the plate D is also pro-

vided with the curved perforation a^4 , which is threaded to receive the correspondingly-threaded end of the screw b^2 , inserted from the under side of the tug-strap, and attaching the 55 same to the plate D and loop C. The plate D is also provided with the posts or pins d d' d^2 d^3 , which serve to assist in retaining the plate and loop C in proper relation. The pins d d^2 also pass through the upper or long end of the 60 chape E, carrying the trace-buckle b^3 , as shown in Figs. 1 and 2 of the drawings. The perforation d^4 in the outer end of the plate D provides for the passage of the screw a^4 , inserted from the upperside, which passes down through 65 both ends of the chape or buckle-strap and secures these ends with reference to each other without being stitched, and terminates in the threaded perforated end d^5 of the long arm b' of the clip B. By this arrangement the several 70 parts are easily and conveniently put together and taken apart, and the worn pieces replaced by new parts without having to replace the whole structure.

The two arms of the clip are connected integrally by the eye F, which serves to attach the tug to the hame. The long arm b extends clear to and is attached directly to the chape or buckle-strap E, while the shorter arm extends but half-way, the plate D forming a continuation, by means of which the different parts are substantially secured together and a great deal of unnecessary stitching saved.

Having thus described my invention, what I claim as new, and desire to secure by Letters 85 Patent, is—

1. The combination, with the hame-tug A, consisting of the two lower parts a a' and the upper shorter part, a^2 , of the metallic clip B, having arms b b' , of unequal length, the longer 90 arm being inserted between the parts a a' and attached to the chape or buckle-strap E, while the shorter arm is sheathed between the part a' and the shorter part a^2 , substantially as described.

2. In a hame-tug, the connecting plate D, provided at one end with the attaching-post a^3 and having the perforations a^4 b^4 in opposite ends of said plate, and the intermediate holding pins or posts, d d' d^2 d^3 , substantially 100 as and for the purpose set forth.

3. In a hame-tug, the combination, with the

connecting-plate D, perforated at each end, and provided with attaching-posts, as described, of the shorter clip-arm b', perforated at the extreme end to receive the post a', and the 5 chape or trace-buckle strap E, whereby said clip-arm and chape are securely connected, substantially as herein set forth.

4. The combination, with the hame-tug A, of the clip-iron B, having arms of unequal 10 length, formed integral by the attaching-eye E, the connecting-plate D, and the buckle-strap

E, all secured together by means of the screw b², inserted from the under side and terminating in the plate D, and the screw a⁴, inserted from the upper side and terminating in the 15 end of the long arm of the clip B, substantially as set forth.

IRA H. TUBBS.
